(57) **CLAIM**

The ornamental design for a rowing machine, as shown and described.

DESCRIPTION

FIG. 1 is a rear, right and top perspective view of a rowing machine, showing my new design;

FIG. 2 is a front, left and bottom perspective view thereof;

FIG. 3 is a top view thereof;

FIG. 4 is a bottom view thereof;

FIG. 5 is a left side view thereof;

FIG. 6 is a right side view thereof;

FIG. 7 is a rear view thereof;

FIG. 8 is a front view thereof;

FIG. 9 is an enlarged view of portion FIG. 1 thereof; and,

FIG. 10 is an enlarged view of portion of FIG. 2 thereof.

The broken lines shown in the drawings illustrate portions of the rowing machine that form no part of the claimed design.
